UNITED STATES PATENT OFFICE.

JOSEF SCHULHOF, OF VIENNA, AUSTRIA-HUNGARY.

MAGAZINE-GUN.

SPECIFICATION forming part of Letters Patent No. 390,099, dated September 25, 1888.

Application filed April 18, 1887. Serial No. 235,966. (No model.) Patented in England July 12, 1886, No. 9,066; in Austria-Hungary July 13, 1886, No. 4,336 and No. 33,443; in France October 5, 1886, No. 178,875; in Belgium October 30, 1886, No. 74,923; in Italy November 12, 1886, No. 8,414; in Spain February 16, 1887, No. 10,452, and in Germany May 5, 1887, No. 38,884.

To all whom it may concern:

Be it known that I, JOSEF SCHULHOF, of the city of Vienna, in the Austro-Hungarian Empire, have invented certain new and useful 5 Improvements in Magazine-Guns, (said invention having been patented to me in the following countries, to wit: in Great Britain July 12, 1886, No. 9,066; in Austria-Hungary July 13, 1886, No. 4,336/33,443; in France October 5, 1886, No. 478,875; in Belgium October 30, 1886, No. 74,923⁶; in Italy November 12, 1886, No. 8,414; in Spain February 16, 1887, No. 10,452, and in Germany May 5, 1887, No. 38,884,) of which I declare the following to be 15 a specification.

This invention relates to improvements in magazine-guns, and has special reference to that class of fire-arms in which a sliding breech-piece or bolt is employed, and wherein the 20 magazine is arranged between the two parts of the stock in immediate connection with the cartridge-chamber in the breech-receiver.

The magazine, which has the form of a drum, is attached to the stock and breech receiver or case underneath the latter, which is 25 in this case provided with a corresponding opening in the bottom to permit the raising of the cartridges from the magazine into the breech receiver or case. This magazine-drum 30 is made to contain from eight to fourteen cartridges, and is, parallel with its axis, provided with an interior central arbor or small drum, around and parallel to which the cartridges are arranged. This interior arbor turns in 35 borings, and is rotated in one direction by the unwinding of a small chain arranged at the one end, the other end of which said chain is attached to the lid of the magazine. Thus when 40 said lid is opened the central arbor of the magazine receives one turn in one direction, when, as the door or lid is fully opened, said arbor is stopped by a spring-pawl catching into a corresponding notch in its end. The other end of this arbor is provided with a spiral spring, which is tightened or wound when 45 the magazine door or lid is opened and the arbor rotated in one direction. By the action of the before-mentioned pawl preventing the

turning back of the arbor the spiral spring is also kept wound until the magazine-door is 50 closed, when a pin, attached to the latter, strikes the pawl, thereby releasing the arbor, which is now turned back into its original position. This turning back causes the feeding of the cartridges into the chamber in the 55 breech case or receiver in the following manner: On its surface, parallel to its axis, the arbor carries a slightly-oscillating lever, which, when the magazine-door is open, stands in its highest position to the right against the lower 60 side of the case. The cartridges having been thrown into the magazine and the door closed, the spiral spring, acting upon the arbor, forces it to turn, whereby said oscillating lever presses laterally against the last cartridge, 65 pushing them all before it, so that one cartridge after the other is passed up an incline, with which the magazine is provided, into the breech-receiver case, where they are struck by the sliding breech piece or bolt, pushed home 70 into the cartridge-chamber, and subsequently fired.

When the gun is to be used as a single loader while the magazine is filled, a slide is pushed into the magazine, which passes over 75 the cartridges and prevents them from passing out.

Figure 1 is a part elevation of the right-hand side of my improved fire-arm, and Fig. 2 a part elevation of the left-hand side of the same. 80 Fig. 3 is a rear view of the magazine with the stock removed and the magazine-flap opened. Fig. 4 is a rear view of the magazine with closed flap. Fig. 5 is a horizontal section of the magazine. Fig. 6 is a top view of the same. 85 Fig. 7 is a front view of the closed magazine. Fig. 6^a is a view of the cartridge-transport lever. Fig. 8 is a vertical section of the closed magazine.

Like letters denote like parts in all the figures. 90

The magazine of my improved gun is, as aforementioned, arranged between the two halves of the shaft, and consists of a drum or casing, *g*, preferably of thin sheet metal, which 95 is attached to the forward and rear halves of

the shaft by means of the lugs p^2 , Figs. 2, 4, and 5, and p' , Figs. 6 and 7, and appropriate screws. A stud or projection, g^6 , of the magazine fits into a suitable recess of the breech-receiver d , 5 so as to fix the magazine to the said breech-receiver. The upper part of the drum g is cut away in order to allow a cartridge to pass through the same, the drum being provided with an incline, g^5 , to enable the ready entrance 10 of the cartridge into the breech-receiver, Fig. 8. The inner walls of the drum are provided with spiral surfaces m , the object of which will be fully described later on in this specification. A second drum or shaft, h , is arranged within 15 and concentric to the walls of the drum g , and has its bearings in the end walls of the same. The shaft h is at its rear end provided with a journal, h^2 , Figs. 3 and 4, to which the chain h^5 is attached. The other end of this chain h^5 20 is attached to the flap g^4 of the magazine, as shown in Figs. 3 and 4. The forward end of the shaft or axis h is provided with a journal, i , around which an appropriate spring, i^2 , is coiled. This spring i^2 is attached to the journal 25 i of the shaft h by pins or screws i^5 i^6 , and to the front end of the drum g , by means of the pin, peg, or screw i^3 , in such manner that when the shaft h is rotated the spring will be put under tension. This movement of the shaft h 30 35 is caused by the opening of the flap g^4 , as follows: The chain h^5 , which connects the flap g^4 of the drum g with the shaft h , runs over a guide pin or roller, h' , Figs. 3 and 4, and is coiled on the journal of the shaft when the drum is closed. This end of the shaft h is provided with an eccentric-disk or offset-wheel, i^4 , in which a pawl, h^3 , gears when the flap g^4 is opened, which said pawl is held in gear with the said disk by means of the spring h^4 when 40 the flap is opened. When the flap is closed, the disk or wheel takes up the position shown in Fig. 4, so that when the flap is opened the chain h^5 will cause the shaft h to make almost one revolution before the pawl comes in gear 45 with the tooth or offset of the disk or wheel, so that the shaft h is held in the position shown in Fig. 3 until the flap g^4 is again closed. In closing the said flap g^4 the pin g^5 comes in contact with the lever-pawl h^3 , so that the same is 50 brought out of gear with the offset or tooth of the disk or wheel i^4 , the chain lays itself loosely against the wheel until the disk or wheel is freed, and is wound on the shaft by the force of the spring i^2 , which was put under 55 tension when the shaft h was rotated in opening the flap g^4 . The so-called "cartridge-trans- 60 porter" on the shaft h , Figs. 5, 6, 6^a, and 8, consists of an oscillating lever, q , on the pivot or screw q^2 q^3 , the movement of which is limited by the length of a slot, i , in which a stud, q^6 , moves. A spring, q' , arranged laterally on the transport-lever q , bears against the shaft h and retains the lever parallel to the said shaft. 65 The operation of the magazine is as follows: In order to fill the magazine the flap g^4 is opened and puts the spring i^2 under tension,

as aforementioned. The pawl h^3 falls at i^4 onto the disk and keeps the shaft h in the position shown in Fig. 3. When the door or flap g^4 is 70 opened, the wheel or shaft h is given one turn and the transport-lever stands in the position shown in Fig. 8, near the opening. The cartridges are now loosely inserted in the magazine and roll around the shaft h , when the 75 weapon is held to the one side until the first cartridge comes in contact with the incline g^5 at the opening or cavity in the breech-receiver, Fig. 8. The magazine is now filled and the door g^4 closed, the pin g^5 releasing the pawl h^3 and 80 giving the shaft h free motion. The spring i^2 , having been put under tension by the rotary movement of the shaft h , has the tendency to return to its original position. The transport-lever q presses against the last cartridge, so that 85 the cartridges are pressed forward until the foremost cartridge is pressed up onto the incline g^5 , and when the sliding breech-piece is drawn back through the opening in the breech-receiver into the cartridge-chamber in the same. 90 In closing the breech the sliding breech-piece a comes against the flange of the cartridge and pushes the said cartridge up the incline g^5 , Figs. 5 and 7, into the cartridge-chamber in the barrel. When the last cartridge has 95 reached the incline g^5 , the transport-lever q is in the position shown by the dotted lines in Fig. 8, and the spring i^2 is released from tension.

It will be evident that the operation of the 100 parts will remain the same whether one or more cartridges are laid in the magazine. If one cartridge is laid in the magazine, the shaft h , and consequently the transport-lever q , will be moved in proportion, so that this cartridge 105 is also brought under the opening or cavity in the breech-receiver. When the magazine is full, the closed breech-piece will prevent a cartridge from rising through said opening or cavity in the breech-receiver, whereas each 110 time the breech-piece is drawn back a cartridge will rise sufficiently, so as to be able to force the same into the cartridge-chamber in the barrel. The flap g^4 , which is hinged at g' to the magazine, is held in closed position by 115 means of a suitable spring-catch. When the sliding breech-piece is drawn back, the flange of the cartridge-shell will strike against a pin, r , fixed to the drum g , and extending through a cavity, r' , in the breech-receiver d , so that the 120 same is ejected.

In order to be able to employ my improved weapon as single loader with filled magazine, I employ a slide, j , which, when not in use, occupies the position represented in Figs. 3, 4, 125 7, and 8. If the said slide j is pushed forward by means of the knob j' , the same will occupy the position, as shown by the dotted lines in Fig. 6, over the cavity or opening of the breech-receiver, and consequently over the 130 opening in the drum and above the cartridges in the same, thus preventing the said cartridges from leaving the magazine. The sliding breech-piece will now glide freely over the

cartridges in the magazine, so that the weapon can be used as single loader until the slide *j* is withdrawn, when the magazine again comes into action. As the magazine is not located immediately beneath the opening or cavity in the breech-receiver, but a trifle to the rear of the same, the inner walls of the drum *g* are provided with spiral guides, so that the cartridges, which originally lay somewhat to the rear of the said opening or cavity in the breech-receiver, will on their way upward be gradually pushed forward until the uppermost cartridge comes in line with the said opening. A rib, *n*, applied to the inner wall of the magazine, serves to hold the cartridge in horizontal position.

The magazine can be readily emptied by simply opening the flap *g*⁴ and allowing the cartridges to roll out. If desired, the walls of the magazine can be perforated at *g*² in order to be able to ascertain whether the magazine is filled or not without having to open the flap.

Having now particularly described and ascertained the nature of my said invention, and in what manner the same is to be performed, I declare that what I claim is—

1. In a magazine fire-arm, the combination, with the stock, barrel, and sliding breech-piece, of a magazine located beneath the breech-receiver, and consisting of a drum or casing, *g*, having a cartridge-receiving opening therein and a hinged flap closing said opening, a rotary shaft, *h*, arranged concentrically within said drum *g* and having journal-bearing within the end walls thereof, a chain, *h*⁵, connected at its ends, respectively, to the rear of the shaft *h* and to the flap *g*⁴, and a spring, *i*², connecting, respectively, the front end of said shaft *h* and the front end of the magazine gun, substantially as and for the purpose set forth.

2. In a magazine fire-arm, the combination, with the magazine-drum *g*, having a flap, *g*⁴, and the rotary feed-shaft *h*, of a disk, *i*¹, secured to one end of said feed-shaft, a spring-pawl, *h*³, located in the rear of the magazine-drum and adapted to engage said disk to hold said flap open, and a pawl-releasing pin, *g*⁵, projecting inwardly from the inner face of the flap *g*⁴, and adapted on the closure of said flap to impinge against and release the spring-pawl, substantially as and for the purpose set forth.

3. In a magazine fire-arm, the combination, with the stock, the breech-receiver *d*, attached thereto, and the sliding breech-pin *a*, contained within said breech-receiver, of the drum *g*, having a hinged spring-held flap, *g*⁴, pin *g*⁵, attached thereto, drum or shaft *h*, provided with a journal, *h*², and chain *h*⁵, which runs over a guide pin or roller, *h*¹, and is coiled on the journal *h*², substantially as set forth. 55

4. In a magazine fire-arm, the combination, with the stock of a breech-receiver, *d*, attached thereto, a sliding breech-pin, *a*, contained within said breech-receiver, drum *g*, having hinged flap *g*⁴ and spiral cartridge-guides *m*, feed shaft or drum *h*, located within the drum *g*, a disk, *i*¹, secured to one end of said feed-shaft, chain *h*⁵, connecting the flap *g*⁴ and shaft *h*, a pin, *h*¹, attached to drum *g* and serving as a guide for said chain, journal *h*², to which one end of said chain *h*⁵ is attached, pawl *h*³, adapted to engage with the disk *i*¹ when the flap *g*⁴ is opened, journal *i*, located on the forward end of shaft *h*, spring *i*², coiled around said journal *i*, and a slide, *j*, adapted to cover the opening of the breech-receiver and retain the cartridges within the magazine, as set forth. 75

5. In a magazine fire-arm, the combination, with the stock, the breech-receiver attached thereto, and the sliding breech-piece *a*, contained within said breech-receiver, of the drum *g*, having an opening therein, hinged flap 85 covering said opening, drum or shaft *h*, pin *h*¹, projecting from one of the faces thereof, journal *h*², located on the rear end of shaft *h*, wheel *h*⁴, located on shaft *h*, pawl *h*³, which engages the wheel *h*⁴ when the flap *g*⁴ is opened, chain *h*⁵, lugs *p*¹ *p*², for attaching the drum or casing *g* to the shaft, pivot or screw *q*² *q*³, transport-lever *q*, located on said pivot or screw *q*² *q*³, incline *q*⁵, located at the opening of the breech-receiver for receiving and guiding the cartridge in its course to said receiver, studs *q*⁶, and ejector *r*, attached to the sliding breech-piece for ejecting the cartridge-shell, substantially as set forth. 95

In witness whereof I have hereunto signed my name in the presence of two subscribing witnesses.
